NEW YORK

DESIGN FOR A CHRISTMAS FLAG

Application filed April 18, 1930. Serial No. 35,312. Term of patent 14 years.

To all whom it may concern.

Be it known that we, SAMUEL CONNOCHIE, a citizen of the United States, residing at and whose post-office address is 43-44 189th Street, Flushing, in the county of Queens and State of New York, and HAROLD WALKER, a subject of Great Britain, residing at and whose post-office address is 24 Vander Venter Avenue, Port Washington, in the county of Nassau and State of New York, have invented a new, original, and ornamental Design for a Christmas Flag, of which the following is a specification, reference being had to the accompanying drawing, forming part thereof.

The figure is a plan view of a Christmas flag, showing our new design.

We claim:

The ornamental design for a Christmas flag, as shown.

SAMUEL CONNOCHIE.
HAROLD WALKER.
